(57) **CLAIM**

The ornamental design for a window treatment as shown and
described.

DESCRIPTION

FIG. 1 is a perspective view of a window treatment showing
our design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment
thereof;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines illustrate portions of the window
treatment which form no part of the claimed design.

The break lines shown in dash-dot broken lines in FIGS.
9-16 symbolize breaks in the length of the article in which
the claimed design is embodied. The appearance of any
portion of the article between the dash-dot break lines forms
no part of the claimed design.
